UNITED STATES PATENT OFFICE

JOHN KOSCO, OF TRENTON, NEW JERSEY, AND CLIFFORD R. APPLETON, OF BRISTOL, PENNSYLVANIA

DESIGN FOR A TABLE GOLF COURSE

Application filed October 9, 1930. Serial No. 37,208. Term of patent 7 years.

To all whom it may concern:

Be it known that we, JOHN Kosco of Trenton, in the county of Mercer and State of New Jersey, and CLIFFORD R. APPLETON of Bristol, in the county of Bucks and State of Pennsylvania, both citizens of the United States, have invented a new, original, and ornamental Design for a Table Golf Course, of which the following is a specification, reference being had to the accompanying drawing, forming part thereof.

The figure is a view in perspective of a table golf course, showing our new design in an open position, the same bearing the outline of a rectangular box when closed and being without surface ornamentation.

We claim:

The ornamental design for a table golf course, as shown and described.

JOHN KOSCO.
CLIFFORD R. APPLETON.
